UNITED STATES PATENT OFFICE.

JOHN MOSCINI, OF NEW YORK, N. Y., ASSIGNOR TO W. H. COE MANUFACTURING COMPANY, OF PROVIDENCE, RHODE ISLAND, A CORPORATION OF RHODE ISLAND.

METALLIC-LEAF-APPLYING DEVICE.

1,344,427.

Specification of Letters Patent. Patented June 22, 1920.

Application filed July 26, 1919. Serial No. 313,600.

To all whom it may concern:

Be it known that I, JOHN MOSCINI, a citizen of the United States, and resident of New York, in the county of New York and 5 State of New York, have invented certain new and useful Improvements in Metallic-Leaf-Applying Devices, of which the following is a specification.

This invention relates to a device for receiving metal leaf from a backing strip and depositing it onto book covers or other surfaces to be ornamented, and has for its object to provide a depositing roll for this purpose carrying means for supplying the 15 metal strip to said roll, the arrangement of the mechanism being such that the strip supplying and applying means may be readily removed from proximity to the roll for the purpose of permitting the roll to be heated without injuring these adjacent parts 20 and as readily return to operative position.

A further object of the invention is to provide means whereby the package roll, the guide for the strip, and the fillet or depositing roll lubricating device, are adapted 25 to be adjusted longitudinally relative to the depositing roll on the operating handle.

With these and other objects in view, the invention consists of certain novel features 30 of construction, as will be more fully described and particularly pointed out in the appended claims.

In the accompanying drawings:

Figure 1— is a side elevation of my improved device for depositing strips of metal leaf, showing the strip supplying parts in full lines in operative position, and in a dotted lines in inoperative position.

Fig. 2— is a sectional edge view of the 40 operating handle showing the supply frame as adjustably connected thereto.

Fig. 3— is an edge view of the roll which guides and presses the metal strip onto the edge of the fillet roll.

The invention contemplates more particularly the provision of a portable instrument adapted to be manipulated by the hand of the operator for the purpose of depositing strips of metal leaf for line work or for 45 forming decorative figures on surfaces to be ornamented.

Referring to the drawings 10 designates the usual fillet or depositing roll which may

be made of different diameters and widths for different kinds of work, and is mounted 55 on the central pin 11 to rotate on the end of the operating handle 12, this handle being slotted longitudinally at 13 to receive the square portion 14 of the supply frame adjusting bolt 15. The upper end 16 of this 60 handle is preferably formed of wood and is for the purpose of manipulating the device.

On the metal portion of the handle 12 I have mounted a plate 17 having a square hole at 18 through which the correspondingly shaped portion 14 of the bolt 15 is passed for the purpose of non-rotatably securing this plate to the handle, and a wing nut 19 is threaded onto the end 20 of the bolt for the purpose of binding the plate 70 in adjusted position.

The upper end of this plate is provided with a hole 21 through which a hinge bolt 22 is passed for the purpose of pivotally connecting the standard or upright frame bar 23 to the plate 17. On the upper end of this frame bar is supported at 24 the reel on which the strip roll of metal leaf 25 is mounted.

Mounted on this frame bar a short distance above its pivoted point is a laterally extending arm 26 on the outer end of which is mounted the guide roll 27 preferably grooved at 28 to engage the edge of the fillet roll to guide and press the strip 29 85 thereto as it is led from the package roll above. I have also provided a guide eye 30 through which the strip of metal leaf and its backing strip may also be led if desired on its way from the package roll to the edge 90 of the depositing or fillet roll.

It is found in practice that the application of a small amount of olive oil, or other suitable greasy substance, to the operating surface or edge of the heated depositing or 95 fillet roll causes the metal leaf to adhere to its surface as it comes in contact therewith and serves to facilitate the depositing of the leaf onto the surface to be ornamented. In order to apply this oil to the roll I have provided a roll or pad 31 which is mounted on the arm 32 pivoted at 33 to swing on the arm 26, and this lubricating roll is flexibly held in contact with the surface of the fillet roll by means of the spring 34, a stop pin 100 38 serving to limit its forward movement.

In order to swing the whole frame forward and press the guide roll 27 onto the edge of the fillet roll I have provided a coil spring 35 one end of which is secured at 5 36 to the arm 26 and the other end is secured at 37 to the plate 17.

In practice it is necessary in order to render effective the operation of the fillet or depositing roll, to heat the same to a moderate temperature by placing the roll over a gas flame, and in order to do this it is found necessary to remove all of the supplying parts, such as the package roll, the guides and the oil roll, from proximity with 10 the fillet roll. To do this in a simple and effective way I simply swing the frame on its hinge from the upright or operative position, illustrated in full lines, back to the inoperative position, illustrated in dotted 15 lines, thereby leaving the fillet roll free and clear to be applied to the heating flame without danger of injuring the other operating parts.

By placing the tension-retaining spring 25 35, as shown, it serves a double purpose; first, to hold the mechanism in operative position with the guide wheel and the oil wheel in contact with the fillet wheel, and second, it also serves to retain the frame in 30 the inoperative position back against the handle 16.

By providing the slot 13 in the operating handle, and a square bolt slidable therein, the supplying mechanism may be adjusted 35 longitudinally on the handle to operate in a practical way with fillet rolls of different sizes.

The strip supplying frame may be connected to the handle to be readily removed 40 therefrom and as readily attached to the handle of another depositing roll, thus avoiding the necessity of equipping all of the depositing rolls in each establishment with a strip supplying frame.

45 The foregoing description is directed solely toward the construction illustrated, but I desire it to be understood that I reserve the privilege of resorting to all the mechanical changes to which the device is susceptible, the invention being defined and limited only by the terms of the appended claims.

I claim.

1. A device for depositing strips of metallic leaf, an operating handle, comprising 55 a depositing roll pivoted to said handle, a frame hinged to said handle, a lubricator for the edge of said roll, a package roll support and a guide for the metal strip all mounted on said frame to coöperate with 60 said depositing roll whereby said frame and said coöoperating members supported thereon may be swung back and so removed from proximity with said depositing roll to permit the latter alone to be applied to a heater 65 without affecting said coöoperating members.

2. A portable device for depositing strips of metallic leaf comprising an operating handle, a depositing roll pivoted upon said handle, a frame hinged to said handle, a 70 lubricator for the edge of said roll, a package roll support and a guide for the metal strip from the package to the edge of the depositing roll, all mounted on said frame to coöperate with said depositing roll 75 whereby said frame and said coöoperating members supported thereon may be swung back and removed from proximity with said depositing roll to permit the application of heat to the latter without affecting its said 80 coöoperating members, and means for retaining said frame either in operative or in inoperative position.

3. A portable device for depositing strips of metallic leaf comprising an operating 85 handle, a depositing roll pivotally mounted upon said handle, a standard hinged to said handle, a package roll support on said standard, a cross arm on said standard, a strip guide roll on said arm, a spring 90 pressed lubricating member supported from said standard and acting upon the surface of said depositing roll, said standard and the roll members supported thereon being adapted to be swung back from proximity 95 with said roll to permit its being subjected to an intense heat without affecting its said coöoperating members.

In testimony whereof I affix my signature in presence of a witness.

JOHN MOSCINI.

Witness:

STUART H. SWALLOW.
